UNITED STATES PATENT OFFICE

101,522

DESIGN FOR A PROJECTOR

Gustave Fassin, Irondequoit, N. Y., assignor to
Bausch & Lomb Optical Company, Rochester,
N. Y., a corporation of New York

Application August 21, 1936, Serial No. 64,500

Term of patent 14 years

To all whom it may concern:

Be it known that I, Gustave Fassin, a citizen of the United States and a resident of the town of Irondequoit, county of Monroe, and State of New York, have invented a new, original, and ornamental Design for a Projector, of which the following is a specification, reference being had to the accompanying drawings, forming a part thereof.

Fig. 1 is a side elevational view of a projector showing my new design, the opposite side pre-

senting substantially the same appearance as the side shown.

Fig. 2 is a front elevation of same.

Fig. 3 is a side elevation of the projector with the film housing in a horizontal position.

Fig. 4 is a top plan view of the projector with the film housing in the same position as in Fig. 3.

I claim:

The ornamental design for a projector as shown and described.

GUSTAVE FASSIN.
